(57) **CLAIM**

The ornamental design for an optical sight system, as shown and described.

DESCRIPTION

FIG. 1 is a perspective view of a first embodiment of an optical sight system showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is a partially enlarged view showing the area "9" in FIG. 8.

The dot-dash broken lines indicating an enlargement portion of the design form no part of the claimed design. The dash-dash broken lines form no part of the claimed design.

1 Claim, 9 Drawing Sheets
